LEROY CLINTON ROBERTS, OF FARMINGTON, CONNECTICUT, ASSIGNOR TO THE AUTOMATIC REFRIGERATING COMPANY, OF HARTFORD, CONNECTICUT, A CORPORATION OF NEW JERSEY

EXPANSION VALVE

Application filed January 19, 1927. Serial No. 162,077.

My invention relates more especially to expansion valves suitable for refrigerating systems.

There has been some recent development in expansion valves to obtain one which would be less seriously affected by the high velocity of the liquid passing the expansion point than the valves ordinarily used. This has resulted in combining two valves to divide the pressure drop existing so that the velocity past the expansion points is divided into two stages, the primary stage employing a pressure range of about 180 lbs., from condenser pressure down to about 60 lbs. The secondary stage works through a pressure range of about 60 lbs., to the pressure in the expansion coils—usually about 15 to 25 lbs. Such a combination has valves using two diaphragms, each diaphragm regulating a valve which is actuated by the desired pressure for the two-stage expansion.

The object of the present invention is to provide means of improved construction for regulating the operation of expansion valves under the control of thermostatic devices located in the refrigerated chamber, so that when the room is cooled to a predetermined temperature, the thermostatic devices will relieve the tension on the expansion valve in such a way as to permit it to close and act as a stop valve.

In its preferred embodiment, my invention contemplates a diaphragm exposed on one side to the pressure fluid on the low pressure side of the expansion valve which is permitted to close whenever there is a sufficient rise of the pressure acting against the diaphragm. Acting against the other side of said diaphragm is a variable pressure medium preferably in the form of a spring, the tension in said spring being changeable under the action of electromagnetically operated means under the control of a thermostat in such a way that whenever the temperature in the refrigerated chamber rises above a predetermined maximum, the load on said diaphragm is increased sufficiently to open the expansion valve and whenever the temperature falls below a predetermined minimum, said load

is reduced sufficiently to permit said valve to close.

Further details of the invention will appear in the description and by reference to the accompanying drawing in which:

Fig. 1 is a schematic view of a two chamber refrigerating plant showing the manner of applying the invention.

Fig. 2 is a sectional view of the combination valve.

Fig. 3 is a sectional view showing a modified form of valve.

Referring first to Figure 1, a compressor 1 is shown driven by an electric motor 2, current to which is supplied from mains 3 and starting switch 4. At 5 is shown a switch which is operated by a back pressure device 6 that operates to start the motor when the back pressure from the refrigerating coils rises to a predetermined point.

At 7 and 8 are shown two refrigerating coils and adjacent to each coil is shown at 9 and 10 electric thermostats that operate to close the circuit from supply conductors 3 to leads 11 and 12 that are connected to solenoid coils 13 and 14. The expansion valve shown at 15 in Fig. 1 is illustrated in section on an enlarged scale in Fig. 2.

The valve body 15 is provided with an intermediate chamber 16 separated from the high pressure pipe 17 by valve 18 and from the low pressure pipe 19 by valve 20. These valves are shown with springs 21 and 22 for pressing them to their seats. A diaphragm 23 bears against the low pressure side of valve 18 and closes an opening to the atmosphere from the intermediate chamber 16. The pressure in chamber 16 therefore tends to press the diaphragm away from the valve and thereby allow the spring 21 to seat the valve. The high pressure in pipe 17 also tends to close the valve. Opposed to these valve closing tendencies is a spring 24 which through a stem 25 may be compressed by a lever 26 pivoted at one end to a fixed member 27, and at its free end to a connecting rod 28 on the end of which is a core 29 of the electric solenoid 13. At 30 is shown a diaphragm controlling the secondary expansion valve 20. A spring 31, as

shown in Fig. 3 under adjustment of screw 32, may be used to apply a predetermined pressure that will allow the valve 20 to open only when the low pressure in the refrigerating coils falls below a predetermined point. In Fig. 2 a construction is shown where the secondary valve 20 has the outside surface of its diaphragm placed under the influence of pressure sensitive to the 10 temperature of the refrigerating room. A chamber over the diaphragm 30 is connected by pipe 33 with a pipe 34 enveloping the last pipe of the refrigerating coils. The pipe 34 is filled with a fluid under pressure, 15 for example, an isolated volume of ammonia drawn from the high pressure system. When the liquid ammonia or other refrigerant reaches the last pipe of the refrigerating coils, the temperature of the fluid in the enveloping casing 34 will be lowered and will contract sufficiently to relieve the pressure on the upper side of the diaphragm 30 so that the valve 20 can close and act as a stop valve. The secondary valve need not be 20 thermostatically controlled. It may be a plain expansion valve as shown in Figure 3, or in some cases a hand operated expansion valve which simply employs a hand adjusted orifice. It is to be observed that the 25 valves are free of stuffing boxes with their attendant leakages and friction.

In operation, when the rooms are cooled to a predetermined temperature, the thermostats 9 and 10 will shut off current from the solenoids 13 and 14, thus releasing the spring tension above the primary diaphragm. This release of pressure causes the primary valve to close and interrupts the flow of refrigerant into the expansion coils. This in turn produces a drop in the 30 back pressure, which may be used to stop the operation of the compressor by the usual back pressure control. When the room temperature rises to the starting point of the thermostat, current is imposed upon the solenoid, which in turn produces a spring tension upon the primary diaphragm, which opens the valve, admitting refrigerant and starts the compressor through the rise in back 35 pressure.

During the running period of the compressor, the pressure underneath the primary diaphragm is the intermediate pressure referred to as being approximately 60 40 lbs., this pressure being maintained constant according to the tension on the diaphragm, as in the usual diaphragm operated valves.

The action of the solenoid is to bring an 45 outside force, that is responsive to the room temperature, to make the primary valve an expansion valve when the room temperature is above the predetermined point and then when the proper temperature is reached to 50 allow the valve to seat positively and act as

a stop valve. When acting as an expansion valve it divides with the secondary valve the work of reducing the pressure and thereby saves considerably the wear due to the rapid flow of fluid. When acting as a stop valve the wear is eliminated altogether.

I claim:

1. In a fluid pressure expansion valve, the combination of a valve-body, a high-pressure pipe, a low-pressure pipe, an intermediate chamber, an expansion valve interposed between said high-pressure pipe and said intermediate chamber, a second expansion valve interposed between said intermediate chamber and said low-pressure pipe, a movable diaphragm operating on each of said expansion valves in a direction tending to open said expansion valve, means for variably loading the diaphragm corresponding to the second-mentioned expansion valve in opposition to the pressure on the low-pressure side thereof, and thermostatically-controlled means for applying different constant pressures of pre-determined magnitudes to the diaphragm corresponding to the first-mentioned expansion valve on the side opposite to that exposed to the pressure in said intermediate chamber.

2. In a fluid-pressure expansion valve, the combination of a valve body provided with a high-pressure inlet, a low-pressure outlet and an intermediate pressure chamber, an expansion valve interposed between said high-pressure inlet and said intermediate pressure chamber, a diaphragm operating on said expansion valve, said diaphragm being exposed on one side to the pressure in said intermediate pressure chamber, a compression spring operative on the other side of said diaphragm in opposition to the pressure in said intermediate pressure chamber, a second expansion valve interposed between said intermediate pressure chamber and said low-pressure outlet, the last-mentioned expansion valve being adapted in cooperation with the first-mentioned expansion valve to maintain a substantially constant predetermined pressure in said intermediate pressure chamber, and thermostatically-controlled means for compressing and relaxing said compression spring for applying different fixed pressures in alternation to the first-mentioned expansion valve whereby it is adapted to operate as an expansion valve when the temperature is above a predetermined point and to operate as a stop valve when the temperature is below said predetermined point.

3. In a fluid pressure valve, the combination of a valve body provided with high-pressure inlet and low-pressure outlet, and an intermediate pressure chamber, an expansion valve interposed between said high-pressure inlet and said intermediate pressure chamber, a second expansion valve inter-

posed between said intermediate pressure chamber and said low-pressure outlet, a diaphragm operative upon each of said expansion valves, each of said diaphragms being exposed on one side to the pressure of the pressure fluid on the low-pressure side of the expansion valve, variable pressure means operative upon the other side of the diaphragm operating on the second-mentioned 5 expansion valve, a compression spring operating on the other side of the diaphragm operating on the first-mentioned expansion valve, and thermostatically-controlled means for imparting a predetermined amount of 10 compression to said compression spring, the first-mentioned expansion valve with its spring under compression and the second-mentioned expansion valve under its variable loading, being adapted to maintain a 15 predetermined substantially constant pressure in the intermediate pressure chamber, said first-mentioned expansion valve being adapted when said compression spring is relaxed, to perform the functions of a stop 20 valve.

4. In a fluid pressure expansion valve, the combination of a valve-body provided with a high-pressure valve-chamber, a diaphragm chamber having a diaphragm forming a 25 movable wall thereof, and a valve-port opening extending between said chambers, an expansion valve for said valve-port opening, said expansion valve being provided with a reduced stem extending through said 30 valve-port opening and into engagement with said diaphragm, said valve body being provided with a second valve-chamber in open communication with said diaphragm chamber, a second diaphragm chamber having a diaphragm forming a movable wall 35 thereof, and a valve-port opening between said second valve-chamber and said second diaphragm chamber, a second expansion valve for the last-mentioned port-opening, 40 said second expansion valve having a reduced stem in engagement with the last mentioned diaphragm, thermostatically controlled means for variably loading the last-mentioned diaphragm, and thermostatically- 45 controlled means for applying different predetermined fixed loads to the first-mentioned 50 diaphragm.

LERoy CLINTON ROBERTS.
